Assignor to

The Lowell Manufacturing Company,
Letters Patent No. 1644, dated Aug. 12, 1862.

The schedule referred to in these Letters Patent and making part of the same.

To all whom it may concern:

Be it known that I, Clemir J. Ney, of Lowell, in the County of Middlesex and State of Massachusetts, have originated and designed a new Pattern for Carpets or other fabrics, of which the following is a full, clear and exact description, reference being had to the accompanying drawings, making part of this Specification.

In corner A, is one fourth of a figure composed of four leaves, meeting on the plain figure, 1. This figure rests upon a ground B, which is interspersed with small crozes and has an irregular border. Fig. C, is a small group of leaves and flowers. All the figures before mentioned are enclosed by the frame work of irregular lines, 2. Corner D, is a quarter of a wreath of flowers from which radiate branches with flowers and sprigs attached. These figures are also enclosed by a frame of irregular lines. 3. E, at the side, is one half of a large group of flowers and leaves.

Fig. 4, is one half of a ground of small crosses, enclosed by irregular lines. Corners, 5 and 6, are sections of figures similar to fig. 4.

The colors employed for the different portions of the design, may be varied to suit the taste and wish of the manufacturer.

— Claim —

What I claim as my invention and desire to secure by Letters Patent, is the design or pattern for Carpets or other fabrics, herein set forth.
